(No Model.)

C. B. CLARK.

GATE.

No. 340,861.

Patented Apr. 27, 1886.

UNITED STATES PATENT OFFICE.

COMMODORE B. CLARK, OF WILLIAMS, CALIFORNIA.

GATE.

SPECIFICATION forming part of Letters Patent No. 340,861, dated April 27, 1886.

Application filed December 31, 1885. Serial No. 187,239. (No model.)

To all whom it may concern:

Be it known that I, COMMODORE B. CLARK, a citizen of the United States of America, residing at Williams, in the county of Colusa 5 and State of California, have invented certain new and useful Improvements in Gates; and I do hereby declare the following to be a full, clear, and exact description of the invention, such as will enable others skilled in the 10 art to which it appertains to make and use the same, reference being had to the accompanying drawings, and to letters or figures of reference marked thereon, which form a part of this specification.

15 My invention relates to certain new and useful improvements in vertically-swinging gates; and it consists in the construction and combination of the parts, as will be hereinafter fully set forth, and specifically pointed out in 20 the claim.

In the accompanying drawings, which illustrate my invention, Figure 1 is a perspective view. Fig. 2 is a side view showing the gate in a position to close or obstruct the gateway 25 in full lines and depressed in dotted lines.

A represents a frame-work which is sunk beneath the bed of the road, and is provided with a transverse slot, *a*, between which the bars *b* and *b'* are pivoted. The lower portion 30 of the transverse slot *a* is trough-shaped and is inclined so that any water that may collect therein will flow out of the opening *a'*.

The frame A is provided at one end with vertical posts B B, which are connected to 35 each other by a cap-piece, B', so as to leave a vertical opening, *c*, between the same, and near the opposite end of the frame A are secured two parallel posts, C C, said posts having attached at their upper ends a cross-beam, 40

D, the ends of which are provided with pulleys *d* *d'*. The uprights or posts C C have secured between the same at a slight distance above the top of the gate a block, E, the end of which is bifurcated, and between said bifurcated portion is pivotally secured a lever, F, which lever extends upwardly so that its end will play between the outwardly-extending bars G, which are attached near the upper ends of the uprights C C. Between the outer 45 ends of the bars G is pivoted a roller, *g*, over which pass cords, which also pass over pulleys *g'*, which are attached above the cross-

beam D, said cords passing from thence over the pulleys *d'*. Guide-pulleys *h* are supported in a suitable frame under the beam D, and 55 around these pulleys pass cords which are attached to the upper end of the lever F, said cords extending outwardly from said pulleys to the pulleys *d*. Thus it will be seen that by drawing upon the cords *e* the lever will be 60 drawn toward the pulley *g*, and when the cords *e'* are pulled upon the lever will be moved in an opposite direction. The bars *b* *b'* of the gate are each at their lower ends pivoted to the side walls of the slot *a*, and the bar *b'* at 65 the end of the gate has a member, *b''*, which projects at right angles thereto, and said member carries at its outer end an adjustable counterbalancing weight, I. The rails *f* *f* of the gate are pivotally attached to the bars 70 *b* *b'*, and the upper rail is provided with a loop or hand-piece, *f'*.

When it is desired to pass through the gate or depress the same within the slot, the cord *e* is drawn downwardly, which will move the 75 lower end of the lever inwardly toward the lower end of the uprights C C, which carries with it the member *b''* of the bar *b'*, the lower end of the lever being connected thereto by a chain, *i*, and after passing over the gate to close 80 the same the cord *e'* is drawn upon, which moves the lever F in an opposite direction, so as to raise the gate, said lever being connected to the member *b'* by the chain *i'*. When the gate is closed, the member *b''* will rest upon the 85 block H, and when the gate is open or depressed below the surface of the road-bed the end of the bifurcated block will serve as a stop, so as to prevent the bar *b''* tilting beyond its center. 90

The pulleys around which the operating cords *e* *e'* pass are protected from the weather by suitable casings or housings.

I am aware of the patent of La Baw, No. 156,888, granted November 17, 1874, and also 95 of the patent of Crandall, No. 111,322, granted January 31, 1871, and I do not claim, broadly, any feature set forth in either of said patented constructions.

I claim—

In a folding gate, a casing located beneath the road-bed and provided with a slot in which are pivotally secured the ends of the bars *b* *b'*, the bar *b'* having a member projecting at right

angles therewith, and provided with a weight, the uprights C C, supporting a bar, D, a frame, G, and block E, in combination with the pulleys d d' g g' h, and cords e e', which pass over said pulleys and are attached to the end of a pivoted lever, F, said lever being connected at its lower end to the bars b' and b'' of the gate, the parts being organized substantially as shown, and for the purpose set forth.

In testimony whereof I affix my signature in presence of two witnesses.

COMMODORE B. CLARK.

Witnesses:

JOHN STANLEY,
H. C. CROWDER.
